INNERSOLE RIB SETTING MACHINE

Jesse V. Poole, Abington, and Charles E. Clarke, Everett, Mass., assignors to Puritan Manufacturing Company, Boston, Mass., a corporation of Massachusetts

Application June 27, 1935, Serial No. 28,620

14 Claims. (Cl. 12—20)

The primary object and main purpose of the machine here illustrated is to increase the firmness of attachment to an innersole body of an originally separate rib strip which has already been connected by adhesive to such a body. An associated object is to compress and consolidate the rib and give it a desired inclination to the plane of the innersole. With these objects in view the essentials of the invention comprise complementary instruments, preferably in the form of rolls cooperatively arranged and driven to apply pressure to the rib and its parts, and at the same time to feed the ribbed innersole with progressive application of pressure lengthwise of the rib.

20 Although the objects of the invention are primarily those above stated, nevertheless such statement is not to be construed as limiting the utility of the invention or the scope of protection claimed for it; since we claim all novel principles and characteristics of the machine for all purposes to which they may be usefully applied.

The drawings furnished herewith show a machine embodying the principles of the invention in the form, arrangement and structure at present preferred to others.

Fig. 1 of the drawings is a front elevation, partly broken away and shown in section, of such machine;

Fig. 2 is a plan view of the machine;

Fig. 3 is a vertical section taken on line 3-3 of Fig. 1;

Fig. 4 is a horizontal section and partial plan taken on line 4-4 of Fig. 3;

Fig. 5 is a detail sectional plan taken on line 5-5 of Fig. 3;

Figs. 3, 4 and 5 are shown on a larger scale than that of Figs. 1 and 2.

40 Like reference characters designate the same parts wherever they occur in all the figures.

The base Π of the machine is provided with legs adapted to rest on a bench or other suitable support, and has a flat upper surface to support the work while passing the operating tools.

Such tools comprise a double conical roll 12, a second double conical roll 13, and a cylindrical roll 14. In the preferred construction, here shown, the roll 12 is secured to a shaft 15 which 50 rotates in bearings 16 and 17, but has no other motion either axially or laterally. Bearing 16 is formed in the rear wall of the base and bearing 17 is formed in an arm 18 which rises from the top of the base in rear of the space in which 55 the work is placed and fed while being acted

upon. Arm 18 extends in a curve upwardly and forwardly to a termination above and clear of the base, and at its extremity is formed with a bore or passage in which is fixed an upright pivot pin 19.

Roll 13 is secured to the lower extremity of a shaft 20 which is both rotatable and movable endwise in separated bearings 21 and 22 in a carrier 23 which is pivotally supported by means of the arm 18 and pivot 19; the carrier having separated eyes 24 at its end remote from that in which shaft 20 is held, which eyes embrace the extremity of arm 18 and receive the ends of pivot 19. Shaft 20 is pressed endwise downwardly by a spring 25 surrounding, and pressing against a collar 26 secured to, the shaft. This spring reacts against the bearing 21 through an interposed ball thrust bearing 27, being confined under tension between the latter and collar 26. The downward movement of this shaft is limited by a belt pulley 28 secured to the shaft adjacent to the upper and outer end of bearing 21. Spring 25 thus causes roll 13 to exert downward pressure on work engaged with the subjacent supporting cylindrical roll 14, and permits roll 13 to yield upwardly when a work piece is inserted, and to accommodate different thicknesses of work.

Roll 13 is movable away from roll 12 by virtue of its pivotal support, previously described. It is yieldingly pressed toward roll 12 by a spring 29 (Fig. 2) which presses against an arm 30 protruding from the side of bearing 22. This spring surrounds a rod 31 which passes freely through an opening in arm 30 and is securely anchored in a fixed arm 32 projecting from the side of the stationary shaft bearing 17. Rod 31 extends forwardly from the arm 30 and has a head 33 between which and arm 30 the spring 29 is confined under compression.

Roll 14 is spring pressed upwardly to support the sole being operated on and press it against the cooperating rolls 12 and 13. Its upper side or limb protrudes through an opening in the top surface of the base. It is secured to a shaft 34 having rotative bearing in the opposite side members of a frame 35 which is connected by a pivot 36 to legs 37 underneath the base, and is yieldingly pressed upwardly by a spring 38. This spring surrounds the shank of a screw 39, which passes freely through an eye 40 in the free end of the frame 35 and is screwed into a boss 41 on the under side of the top surface of the base. Spring 38 is confined between the head on the lower end of screw 39 and the eye

40. Boss 41 establishes the upper limit to which the roll 14 may be moved by the spring.

Rolls 12 and 13 are independently driven from a countershaft 43 mounted in a bearing 44 at 5 one end of the base. This countershaft is driven by a pulley 45 and belt 46. It carries two other pulleys 47 and 48; the former of which drives by means of belt 49 a pulley 50 on the outer extremity of shaft 15, while pulley 48 drives by a belt 51 10 the pulley 28 previously described as being secured to roll shaft 20. Shaft 34 of roll 14 is driven from shaft 15 by bevel gears 52 and 53.

As shown, the axes of all the rolls are in the same plane; and the rolls are so related to one 15 another in this plane that the rolls 12 and 13 are adapted to grip between them the rib *a* of an innersole *b*, while at the same time these two rolls cooperate with roll 14 in pressing the flanges *c*, *d* of such rib against the surface of the sole. 20 The springs acting on rolls 13 and 14 as described permit these rolls to separate from each other and from the nonyielding roll 12 when a sole, with lightly attached rib, is passed between them in the manner shown in Figs. 3 and 4, and cause 25 them to press firmly, and with pressure limited only by the strength of the springs, in the directions necessary to insure firm contact of the rib flanges with the sole and compacting of the rib itself. The rim or ridge between the opposed 30 conical faces of each of the rolls 12 and 13 is preferably made sharp or fine enough to enter fully into the corresponding contiguous angle between the rib and its adjacent base flange, making a well defined angle in the work, and, in 35 particular, insuring a close contact directly at the base of the rib with the sole. In fact the angles of the conical faces may be so disposed as to concentrate the pressure at these rims or ridges if desired. But at the same time they are 40 not so sharp as to cut the material of which the rib is made.

The face 12a of roll 12 and 13a of roll 13, that is the conical faces which grip the rib between them, are preferably fluted in order to secure a 45 firm enough grip to feed the work steadily and smoothly. These faces in their intersections with the common axial plane may be parallel to one another, or somewhat convergent or divergent if desired; and may be perpendicular or inclined to 50 the contiguous face of roll 14, as needed either to set the rib upright with respect to the plane of the sole, or at any desired inclination. Also the faces 12b and 13b of these rolls may be parallel to the surface of the roll 14 in the axial plane, if 55 desired to exert an even pressure throughout the entire width of the base flanges *c* and *d*; or they may be at acute angles to the roll 14 if it is desired to concentrate the pressure in the angles between the rib and its flanges. These effects are 60 obtainable within a considerable range of values of the angles made by the roll axes with one another and of angles made by the conical faces with the respective axes of the rolls. Substantially, the shafts 15 and 20 are at acute angles 65 to the shaft 34, and at nearly right angles with one another; although considerable variation in the angle between the shafts 15 and 20 may be made from that shown without departing from the principles of the invention.

70 In the operation of the machine for the purpose herein described, an innersole to which a rib has first been attached by adhesive is introduced in the manner shown in Fig. 4. One end of the rib is placed in the nip of the rolls 12 and 13 75 while the sole itself and the flanges of the rib

are brought between these rolls and the under roll 14. Rotation of the rolls by the driving means described feeds the sole by the tractive effect of all the rolls, and pressure is thus progressively applied to all points in the length of 5 the rib.

A guide or gauge roll 55 is mounted on the upper face of the machine base by an adjustable bracket 56 so as to bear on the edge of the sole at a point back of the pressure rolls to insure starting of the work in the right direction. A guide finger 57 is secured to the arm 32 previously mentioned and projects partly around and under the roll 12 toward the gripping point, in position to enter the outer angle and engage the outer side of the 10 rib, preventing the rib from being crushed between rolls 12 and 14. With the assistance of such guides, the rolls are able to feed the work without assistance by the operator after the work piece has once been placed in the machine as 15 described. The driving means (belt pulleys and gearing) are designed of such values as to give substantially equal peripheral speeds to the largest circumferences of all three rolls.

For convenience in distinguishing the rolls 20 from one another by name, the roll 14 may be called the backing or reaction roll, the roll 12 may be called the outer rib-engaging roll, and roll 13 may be called the inner rib-engaging roll.

In this illustration the rib is shown as composed of a folded strip of fabric with a stiffening core or strip within the central fold which forms the rib proper. And it is to be understood that the strip thus folded is ordinarily coated on one side with an adhesive of any suitable kind before 30 being folded and placed on the surface of the body. It is to be understood, however, that ribbed innersoles otherwise constructed may be operated on by the machine; and also that the machine may be put to any other useful purpose 35 for which it is adapted. Hence the title used as a convenient designation in this specification and in the following claims is to be construed simply as such and without limiting implications.

What we claim and desire to secure by Letters 45 Patent is:

1. An innersole rib setting machine comprising a supporting structure, two double-conical rolls mounted with one conical surface of each substantially parallel to the other at their adjacent 50 sides and relatively located to grip the rib of such an inner sole between them, one of said rolls being mounted with capacity for movement toward and away from the other, a spring pressing said movable roll toward the other, and a reaction 55 roll arranged to hold the body of the sole, and base flanges of the rib, with pressure against the other conical faces of said rolls.

2. An innersole rib setting machine comprising shafts of which the axes are related to one 60 another as the three sides of a triangle, and rolls mounted on the respective shafts, one of said rolls being cylindrical and the other rolls having conical faces respectively complementary to said cylindrical roll and to one another arranged to press simultaneously against the opposite sides of an innersole rib and against the base flanges of such rib and the body of an innersole.

3. A machine of the character described comprising a roll having a cylindrical face and two 70 cooperative rolls having conical faces complementary to said cylindrical roll and other conical faces complementary to one another.

4. A machine of the character described comprising a roll having a cylindrical face and two 75

cooperative rolls having conical faces complementary to said cylindrical roll and other conical faces complementary to one another, and means for driving said rolls with substantially equal 5 peripheral speeds at their largest diameters.

5. A machine of the character described comprising a roll having a cylindrical face and two cooperative rolls having conical faces complementary to said cylindrical roll and other conical 10 faces complementary to one another, said rolls being mounted with provision for relative separation from one another, and yielding means forcing them relatively together.

6. A machine of the character described comprising three cooperative rolls arranged with their axes substantially in the same plane and angularly inclined to one another, two of said rolls having conical faces related to one another so as to grip an interposed innersole rib between 15 them throughout substantially the entire height of such rib, and the third roll being related to the first two so as to cooperate with them in gripping interposed material, and driving means engaged and correlated with said rolls to rotate 20 them all, independently of interposed work, with substantial equal linear velocities at their greatest circumferences; said rolls being mounted for relative movement to enlarge and contract the spaces 25 between each roll and each of the other two, and being spring pressed in directions to contract such spaces.

7. A machine for the purpose described comprising a double conical roll adapted to enter the outer angle between the body and rib of an 30 innersole, a complementary double conical roll adapted to enter the inner angle between such sole and rib, a third roll arranged to bear against the opposite side of an innersole from the before named rolls, means for driving said rolls at substantially the same linear speed at their largest 35 circumferences and in the same direction at their point of closest approach to one another, and a guide finger associated with the first named of said rolls extending partly around and under the 40 circumference thereof into the outer angle of the rib, arranged to prevent entrance and crushing of the rib between said roll and the last named roll.

8. A machine of the character set forth comprising a base, a shaft mounted rotatably in said 45 base, a roll secured to one end of said shaft, a second shaft extending across the outer end of said roll, a second roll on the end of said second shaft located in cooperative work-gripping relationship with the first roll, driving means for 50 rotating both of said shafts, a carrier in which the second shaft is supported, said carrier being mounted to permit movement of the second shaft and roll away from and toward the first roll in a path substantially parallel to the gripping surface of the after named third roll, a spring acting 55 on said carrier so as to force the second roll toward the first roll, a third roll located in position to grip material between its outer surface and both of the before named rolls, means mounting the third roll to permit its movement 60 toward and away from the other rolls, and spring means forcing the third roll toward the first two rolls.

9. A machine of the character set forth comprising a base, a shaft mounted rotatably in said 65 base, a roll secured to one end of said shaft, a second shaft extending across the outer end of said roll, a second roll on the end of said shaft located in cooperative work-gripping relationship 70 with the first roll, a carrier in which the second

shaft is mounted, said carrier being mounted movably so as to permit movement of the second shaft and roll away from and toward the first roll, a spring acting on said carrier so as to force the second roll toward the first roll, a 5 third roll located in position to grip material between its cylindrical outer surface and both of the before named rolls, spring means acting on the second shaft with tendency to force the second roll endwise toward said third roll, means 10 mounting the third roll to permit its movement toward and away from the other rolls, and spring means forcing the third roll toward the first two rolls.

10. A machine of the character set forth comprising a base, a shaft mounted rotatably in said base, a roll secured to one end of said shaft, a second shaft extending across the outer end of said roll, a second roll on the end of said shaft located in cooperative work-gripping relationship 15 with the first roll, a carrier in which the second shaft is mounted, said carrier being mounted movably so as to permit movement of the second shaft and roll away from and toward the first roll, a spring acting on said carrier so as to force the second roll toward the first roll, a third roll located in position to grip material between its outer surface and both of the before named rolls, means mounting the third roll to permit its movement 20 toward and away from the other rolls, spring means forcing the third roll toward the first two rolls, and a guide finger extending partially around the circumference of the first roll toward the nip of said roll with the second and third 25 rolls.

11. An innersole rib setting machine comprising a base structure having a normally horizontal work supporting top and an arm rising from said base structure and extending laterally and forwardly from its union with said structure, a shaft 30 rotatably mounted in bearings in said arm and base structure at an inclination to said work supporting top, a roll secured to one end of said shaft above the work supporting top, a roll carrier pivoted to the extremity of said arm so as to swing about an axis perpendicular to said top, a shaft mounted rotatably in said carrier in a position near to and extending substantially diametrically across said roll, a roll mounted on the extremity of said last-named shaft in relation to 35 the first named roll to grasp between itself and the latter the rib of an innersole, a spring acting on said carrier to force the second named roll toward the first named roll, power means for rotating said rolls in the same work-propelling 40 direction, and spring actuated means arranged to engage an innersole at the opposite side thereof from the rib and press the innersole upwardly 45 toward the rolls.

12. A rib setting machine as set forth in claim 11, in which the spring actuated means comprises a yieldingly mounted roll protruding through the work supporting top between the precedently named rolls, and a spring acting upwardly on said last named roll.

13. A rib setting machine as set forth in claim 11, in which the spring actuated means comprises a frame pivoted beneath said work supporting top and movable angularly in a path transverse to said top, a spring acting on said 50 frame to force it upwardly, and a roll carried rotatably by said frame protruding through the work supporting top beneath the previously named rolls.

14. A rib setting machine as set forth in claim 75

11, in which the spring actuated means comprises a frame pivoted beneath said work supporting top and movable angularly in a path transverse to said top, a spring acting on said frame to force it upwardly, and a roll carried rotatably by said frame protruding through the work supporting top beneath the previously

named rolls, and comprising further gearing between the last named roll and the first named shaft whereby said roll is rotated in harmony with the two precedently named rolls.
